UNITED STATES PATENT OFFICE.

JAMES C. DUNBAR, DECEASED, LATE OF WINNIPEG, MANITOBA, CANADA; BY MARY EMMA DUNBAR, ADMINISTRATRIX, OF WINNIPEG, MANITOBA, CANADA.

COMBINED PRINTING AND AUTOGRAPH MACHINE.

Application filed October 25, 1923. Serial No. 670,792.

To all whom it may concern:

Be it known that I, MARY EMMA DUNBAR, of the city of Winnipeg, in the Province of Manitoba, Canada, widow, and administratrix of the estate of JAMES C. DUNBAR, deceased, in his lifetime of the said city of Winnipeg, printer, and that the said JAMES C. DUNBAR did invent a certain new and useful Improvement in Combined Printing and Autograph Machines, of which the following is the specification.

The invention relates to a combined printing and autograph machine and an object of the invention is to provide a machine or device by means of which a merchant, such as a grocer, can print his own memo blanks or forms in duplicate progressively with their use and note his sales on the printed blank as he now does upon what is known as a printed counter check book supplied him and by so doing make considerable saving in his printer's bill.

A further object of the invention is to construct the machine in a simple, durable and inexpensive manner and so that access can be readily had to all working parts for inking, setting or repairing purposes, if needs be.

A further object of the invention is to provide the device with means whereby the merchant can easily and quickly feed the paper from the machine, enter the account of his sale on the printed sheet, detach the sheet so entered and reset the machine for the following bill.

A further object is to construct the machine so that no trouble is experienced or time lost in setting the machine to make the duplicate bill.

With the above more important objects in view the invention consists essentially in the arrangement and construction of parts hereinafter more particularly described and later pointed out in the appended claims, reference being had to the accompanying drawings in which:

Fig. 1 is a side view of the complete machine with the paper removed.

Fig. 2 is a plan view of the machine as above.

Fig. 3 is an enlarged detailed longitudinal

sectional view centrally through the machine.

Fig. 4 is a horizontal sectional view through one side of the machine, the section being taken at 4-4' Figure 3.

Fig. 5 is a vertical sectional view at 5-5' Figure 3 and looking forwardly.

Fig. 6 is a vertical cross sectional view at 6-6' Figure 3 and looking rearwardly.

Fig. 7 is a vertical cross sectional view at 7-7' Figure 3.

Fig. 8 is a perspective view of the roller carrier frame.

In the drawings like characters of reference indicate corresponding parts in the several figures.

The machine casing 1 which contains the various rollers, later described, is preferably formed from sheet metal and is of neat design and appearance, the front end being partially closed by a cross plate 2 and the rear end being wholly closed by a hinged gate or door 3 which can be latched. The bottom of the casing is closed and the side walls thereof are provided with upper and lower pairs of opposing horizontally disposed spacers 4-4' and 5-5', these spacers guiding the roller carrying frame work 6 which is slid into place within the casing through the door 3, the bottom of the frame work sliding on the bottom of the casing and the sides thereof being guided by spacers.

The frame work 6 comprises upper and lower pairs of lengthwise extending bars 7 and 8, 9 and 10, the bars of the pairs being connected by vertically disposed plates 11, 12 and 13 suitably spaced. These bars are permanently riveted together and are of fairly heavy stock so that they will not twist or bend.

In the present application I have not shown the side members of the frame work as connected one to the other. This could be done if desired by utilizing cross braces.

The side members of the frame work carry forwardly a type or printing roller 14 which is positioned above an under guide roller 15, the rollers being carried by cross shafts or spindles 16 and 17 which have their ends 100 projecting beyond the ends of the rollers and rotatably mounted in the vertical plates

13. The opening or bearing 18 for the top shaft in each plate is made so that the shaft can move a limited amount vertically, this permitting the top roller to bear continuously and heavily on the paper passed between the rollers as later described.

Associated with the printing roller I have an inking, platen, or bed roller 19 which is carried by a shaft 20, the ends of the shaft 10 being mounted in vertical slots 21 provided in the top bars 7 and 9. The lower ends of the slots are deflected towards the roller 14 so that the printing roller which is purposely made heavy will press against 15 the face of the roller 14. To the rear of the rollers 14 and 15 I locate a pair of idler rollers 22 and 23 carried by the plates 12, the shaft 24 of the top roller being mounted in elongated vertical openings 25 20 provided in the said plate, such permitting of a limited vertical movement of the roller. These idler rollers serve to guide the paper to the rollers 14 and 15.

The plates 11 carry rotatably a cross shaft 25 26 which supports a spool 27. The shaft 26 has the ends thereof entered in more or less L-shaped slots 28 provided in the plates 11, such slots permitting of the putting in place of the spool from the back.

30 By making the side members of the frame work 6 independent one of the other it is a very easy matter to put the rollers in place. After they have been placed one simply slides the side members into position within 35 in the casing through the rear end thereof.

The printing roller in the present instance is fitted with a tubular printing form 29 of cylindrical shape, it being important that it fit closely and uniformly on the roller and be firmly secured thereto. The form which 40 I use is what is commonly known as a rubber stamp, the rubber strip being placed around the face of the roller and securely cemented thereto. The said printing roller is adapted, when inked, to print the paper passed between the printing roller and the roller 16 in the usual form as used by a merchant, such as a grocer, for rendering a bill. The printed lines are partially indicated in Figure 4 of the drawing.

50 A felt of such like ink absorbing strip is wound around and permanently secured to the face of the roller 19.

This machine is adopted to receive two rolls 55 of paper, one roll for the original printed bill and the other for the duplicate thereof. To this end two strips of paper are simultaneously wound around the spool 27 so that the strips will feed from the spool and provide an upper strip 30 and an under strip 31. These two strips of paper are passed between the rollers 22 and 23 and those 14 and 15 and obviously as the strips are pulled 60 forwardly through the front end of the machine the upper face of the top strip 30 will

be printed by the form 29 which is inked by the felt pad of the roller 19.

At the front end of the machine I provide convenient means for supporting the paper strips so that they can be written upon, also means for withdrawing the strips each time a sale is made and also means for conveniently making the carbon or duplicate copy of the sale entered. Such parts are now described.

75 The front lower part of the machine is extended to provide a slightly inclined top plate or writing table 32 over which the sheets of paper 30 and 31 are drawn and on which the sales entries are made from time to time. The edges of the table extend beyond the sides thereof to provide guides and on the table I mount a sliding plate 33 which has the ends thereof turned downwardly as indicated at 34, the turned down ends co-acting with the extended edges of the table to retain the sliding plate in place. The sliding plate has the forward edge thereof upturned to provide a locking flange 35 and it is fitted at the rear edge with 90 corner stops 36 which limit the rear travel of a combined shifting and locking plate 37. The locking plate is slidably mounted on the plate 33, this being accomplished by

95 downturning the ends of the plate 37 as best shown in Figure 6. Spaced strips 38 and 39 are inserted between the edges of the plates 33 and 37, these spacers holding the plates apart a fixed distance equal to the thickness of the two sheets of paper 30 and 100 31 passed therethrough. Obviously the stops limit the backward movement of the plate 37 and the forward movement thereof is limited by the contact of the forward ends of the spacers with the flange 35, this occurring when the forward edge of the plate 37 is practically engaged with the flange. The strips of paper 30 and 31, after 105 passing between the plates 33 and 37 pass over the flange and then lie on the face of the table, with the result that one can, by advancing the plate 37, securely grip the two sheets of paper between the flange 35 and the advanced edge of the locking plate 37. A hand grip 40 is secured to the plate 37 and 110 it is provided also at the front edge with a forwardly extending straight edged tearing plate 41.

115 After one has advanced the locking plate to grip the strips of paper he can, by further advancing the locking plate, cause the sliding plate to advance and in so doing pull the strips of paper over the face of the table. The forward position of the advanced plates is limited by a stop 42. After the strips of paper have been brought to the latter position the locking plate is moved back to engage the stops 36 and thereafter both plates are carried back to their original position at the rear end of the table. This leaves the 120

pulled out strips of paper lying on the face of the table and in a position such that a bill of sale can be conveniently made out on the upper printed sheet.

- 5 In order to make the duplicate or carbon copy of the sale I have provided a carbon sheet holder 43 which comprises a substantially L-shaped side bar 44 carried by a lengthwise extending side shaft 45 rotatably 70 mounted in suitable bearings attached to the right hand side of the table. The bar 44 carries two pairs of spring arms 46 and 47 suitably spaced apart and adapted to receive between them a carbon sheet 48. The 75 15 spring arms have their right hand ends permanently attached to the bar 44 and their left hand ends detachably connected together by demountable clips 49 and 50. This latter arrangement permits of the renewal of the carbon sheet from time to time 80 by simply removing the clips, then inserting the new sheet and subsequently replacing the clips.

The general arrangement of the holder is 85 such that when in use the carbon sheet will lie directly over the strip 31 when the same is extended over the table. Consequently when a bill of sales entry is made on the printed top sheet the carbon sheet will make 90 30 a duplicate copy on the underlying strip.

During the interval that the sliding plate and locking plate are being pulled ahead and returned to their original position the carbon sheet holder occupies a position to 95 35 the side of the machine with the carbon sheet extending upwardly and the bar 44 entirely clear of the path of travel of the moving plates. A thumb piece 51 is attached to the carbon sheet holder so that 100 40 the same can be easily and quickly thrown up or down.

After one has returned the sliding plate and locking plate to their inner position he lifts the top strip 30 and swings the carbon sheet into a position above the bottom strip 31. He then lets the top strip take its 105 45 position over the carbon strip and can at this time make his bill of sale. This having been done, the carbon holder is swung to the side and the locking plate and sliding plate are again shifted to their forward position.

This movement passes the bill made out in duplicate ahead and brings forward a 110 50 new printed strip with its underlying duplicate. The made out bill is torn off, this being facilitated by the tearing plate 41. This being done, the locking plate and sliding plate are returned to their original position, the carbon sheet is subsequently entered into place and one is ready to make a 115 55 new entry or bill of sale.

Whilst I have shown the table integrally formed with the casing of the machine, I do 120 60 not desire to be limited to this construction

as it might be necessary for storing and shipping purposes to have the table demountable. This is a very easy matter as all the working parts associated with the table are entirely independent of the casing 70 and it would only be a matter of demountable connecting the inner end of the table in any suitable manner to the forward end of the casing.

What I claim as my invention is:—

1. In a combined printing and autograph machine, an outer casing, a frame work insertable within the casing and presenting side members, a guide roller rotatably carried by the side members of the frame work, a printing roller above the guide roller and rotatably carried by the side members of the frame work, an inking roller rotatably carried by the side members of the frame work and contacting with the printing roller, a pair of idler rollers positioned to the rear of the guide roller and a removable spool carried by the rear end of the frame work and provided with a roll embodying duplicate strips, the ends of the strips passing from the roll forwardly between the idler rollers and between the guide roller and the printing roller and a table at the forward end of the machine on which entries can be made on the uppermost of the strips passed thereover.

2. In a combined printing and autograph machine, a casing having the forward end thereof partially open and the rear end thereof normally closed by a gate, a roller carrying frame work insertable within the casing through the gate and presenting side members, a guide roller positioned forwardly of the frame work and carried by the side members thereof, a printing roller riding the guide roller and carried by the side members of the frame work, an inking roller carried by the side members of the frame work and riding the printing roller, a pair of contacting idler rollers carried centrally by the side members of the frame work, a removable rotatable spool carried rearwardly by the side members of the frame work, duplicate strips of paper wound on the spool, said strips having their free ends passed forwardly between the idler rollers and between the printing roller and the guide roller and out the front end of the casing and a writing table located at the front end of the casing and carrying the extending ends of the strips.

3. In a combined printing and autograph machine, a casing having a partially open front and the rear end thereof normally closed by a gate, pairs of upper and lower lengthwise extending spacing bars secured permanently to the side walls of the casing, opposing similar side frames insertable within the casing through the gate and bearing against the spacers, a rotatably mounted

ed guide roller carried forwardly by the side frames, a printing roller riding the guide roller and also carried by the side frames; an inking roller rotatably carried by the side frames and contacting continuously with the printing roller, a pair of idler rollers rotatably carried by the side frames and positioned rearwardly of the former rollers, a removable spool rotatably carried by the rear ends of the side frames, duplicate strips wound around the spool and having their outer ends extended forwardly between the contacting rollers and out through the open forward end of the frame and a table located at the forward end of the casing and receiving the extending ends of the strips.

4. The combination with a guide and a printing roller and a roll embodying duplicate strips withdrawable from the roll between the rollers, of a table on which the withdrawn ends of the strips can rest, means carried by the table for releasably grabbing the strips to extend them over the table and a duplicating sheet associated with the table and insertable between the strips upon the same being withdrawn over the table.

5. The combination with a guide and a printing roller and a roll embodying duplicate strips withdrawable from the roll between the rollers, of a table for supporting the withdrawn strips, releasable strip grabbing means carried by the table and endwise shiftable thereon and a duplicating sheet associated with the table and insertable between the strips in the withdrawn position thereof.

6. The combination with a guide and a printing roller and a roll embodying duplicate strips withdrawable from the roll between the rollers, of a table for receiving the withdrawn ends of the strips, a plate crossing the table and endwise slidably thereon, said plate having the forward edge thereof upturned, a locking plate slidably carried by the former plate and spaced therefrom to permit of the passage between the plates of the strips, said locking plate being adapted, when shifted towards the upturned end of the other plate, to grab and hold the strips, and a carbon sheet holder pivotally attached to the side of the table and adapted, when swung over the table, to permit of the placing of the carbon sheet between the strips.

7. The combination with a machine for printing the upper of duplicate paper strips, the duplicating strips being pulled from a roll in the machine to effect the printing, of a table located at the front end of the machine and over which the strips are pulled and on which entries can be made on the strips, means carried by the table for releasably gripping the strips in a location adjoining the machine and for subsequently

pulling the gripped strips over the table, said means being re-settable thereafter at the opposite end of the table and means for inserting a carbon sheet between the withdrawn ends of the strips.

8. The combination with a machine for printing the upper of duplicate paper strips, the duplicating strips being pulled from a roll in the machine to effect the printing, of a table located at the front end of the machine and over which the strips are pulled and on which entries can be made on the strips, means slidably carried by the table and movable towards and away from the machine, means associated with said latter means permitting of the gripping of the strips adjoining the machine and the release of the gripped strips in a location away from the machine and means for inserting a carbon sheet between the ends of the withdrawn strips.

9. The combination with a machine for printing the upper of duplicate paper strips, the duplicating strips being pulled from a roll in the machine to effect the printing, of a table located at the front end of the machine and over which the strips are pulled and on which entries can be made on the strips, a plate slidably mounted on the table and movable endwise thereon towards and away from the machine and over which the sheets pass, said plate having the side remote from the machine upturned to provide a gripping flange, a plate slidably mounted on said former plate and adapted to be advanced towards the flange to grip the strips and a carbon sheet holder associated with the table and insertable between the strips.

10. The combination with a machine for printing the upper of duplicate paper strips, the duplicating strips being pulled from a roll in the machine to effect the printing, of a table located at the front end of the machine and over which the strips are pulled and on which entries can be made on the strips, a plate slidably mounted on the table and movable endwise thereon towards and away from the machine and over which the sheets pass, said plate having the side remote from the machine upturned to provide a gripping flange, a plate slidably mounted on said former plate and adapted to be advanced towards the flange to grip the strips and a carbon sheet holder pivotally attached to the side of the table and inwardly swingable over the table to take a position between the strips.

11. The combination with a machine for printing the upper of duplicate paper strips, the duplicating strips being pulled from a roll in the machine to effect the printing, of a table located at the front end of the machine and over which the strips are pulled and on which entries can be made on the strips, releasable means carried by the table

for gripping the strips and pulling the same over the table, said means being re-settable after the strips have been pulled over the table and a carbon sheet holder pivotally attached to the side of the table and adapted to be swung over the table to permit the carbon sheet to take a position between the strips after the strip gripping means has been returned to its original position.
